PRINTING MACHINE

Clyde Smith, Hopkinsville, Ky., assignor to Ad-
dressograph-Multigraph Corporation, Cleve-
land, Ohio, a corporation of Delaware

Application August 12, 1936, Serial No. 95,589

50 Claims. (Cl. 101—58)

This invention relates to printing machines of the kind adapted for printing addresses, salutations, lists and similar matter under control of control devices such as punched cards and the like.

Addresses, salutations and the like usually consist of a plurality of vertically spaced horizontally extending lines and it is sometimes desirable to print these lines in a single line or row as in the preparation of lists such as those used by the publishers of periodicals, mail order houses and the like to enumerate their subscribers, customers and so forth. The primary object of my invention is to enable addresses and the like to be printed either in a plurality of vertically spaced lines or in a single line or in other arrangement that may be desired.

In preparing lists wherein the parts of the address ordinarily printed in vertically spaced lines are printed in a single line it is sometimes desirable to print the various parts of an address in different arrangement as, for example, in some instances it is desirable to print the name part of an address first, the street and number part of an address next and the city and state part of an address last, while in other instances it may be desirable to print the city and state part first, the street and number part second, the name part third and in other instances it may be desirable to print the parts in a still different order, and another important object of my invention is to enable the various parts of an address to be printed in any desired order.

In those machines wherein addresses and like matter are printed under control of punched cards or similar control devices it is often desirable to enter the records on the punched cards in registers so that the addresses may be stored and printed after the record card or other control device is passed from the machine, and a further object of my invention is to enable such storing of the records of control devices, and ancillary objects are to selectively and simultaneously print the data represented by the records and to release the records from the register or to print the data without releasing the records from the registers or to enable an entire address to be printed and to simultaneously release but a single part of the particular record entered in the registers.

Still further objects of the invention are to store the records of punched cards or other control devices in registers; to effect set-up of the registers under control of the records in the punched cards; and to maintain the set-up of

the registers after the punched cards or other control devices have passed from the machine whereby the records may be retained in the registers and utilized and released when and as desired.

Other objects of the invention are to enable various parts or lines of addresses to be independently printed and thereby enable the simultaneous printing of different parts of different addresses; to synchronize the printing of different parts of different addresses and thereby enable the printing to proceed as rapidly as if all parts of an address were printed in a single operation; to enable all parts of an address to be simultaneously printed at the same time selected parts thereof are being printed; to operate a plurality of printing elements under control of records entered in registers; to selectively operate a plurality of printing elements under control of records entered in registers; and to provide a simple and economical novel printing machine controllable by record cards or like control devices in an efficient and positive manner.

A selected embodiment of my invention is illustrated in the accompanying drawings wherein

Fig. 1 is a diagrammatic view of the line by line printing elements and the sheet feeding mechanism therefor and wherein a part of the electrical circuits is illustrated;

Fig. 2 is a diagrammatic view of three groups of register relays and the control relays therefor as well as a part of the circuits for the register and control relays;

Fig. 3 is a diagrammatic view of the control cams, contact bars and fingers and wherein another part of the electrical circuits is illustrated;

Fig. 4 is a diagrammatic view of the straight line printing elements and wherein still another part of the electrical circuits is illustrated;

Fig. 5 is a vertical sectional view of the card feed and contact bars;

Fig. 6 is a top plan view of the card feed and a perspective view of the control cams;

Fig. 7 is a view drawn to an enlarged scale of a typical printing element employed in the machine; and

Fig. 8 is a view showing three record cards of the kind under which the machine may be controlled.

The form of my invention illustrated in the accompanying drawings is under control of record cards on which the character symbols in the form of perforations are arranged under a five-unit code but my invention is not limited to use with perforated cards nor to the use of cards

perforated under a five-unit code for, as will be apparent to one skilled in the art, cards may be perforated in accordance with a six-unit or any other desired code or the cards may be perforated to directly represent character symbols without the use of a multiple unit code or control devices other than perforated cards may be used without departing from the ambit of the invention.

10 Moreover, I have shown a machine for printing a three-line address inasmuch as this is the usual arrangement of an address in the art but it is to be understood that by duplicating certain of the mechanisms the machine might be adapted 15 for printing a four-line address or by eliminating some of the mechanisms the machine could be used to print a two-line address.

Furthermore, I have shown the printing elements as being set up under control of electro-magnetically operated means but it is to be understood that code disc selectors or other suitable means may be employed without departing from the purview of my invention.

In the accompanying drawings I have illustrated the various mechanisms conventionally inasmuch as the specific construction of the elements may be varied within a wide range of limits as will be understood by reference to the following detailed description.

30 *Register, shift and transfer relays—Fig. 2*

Inasmuch as I have shown my invention as embodied in a machine adapted for printing a three-line address three groups of registers A, B 35 and C are provided, each of which groups includes three rows of five relays as 10, 11, 12, 13 and 14, each of such rows constituting a register. In the present instance, the relays 10 to 14, inclusive, constitute the first register of the group A for the 40 first line of an address; the relays 15 to 19, inclusive, constitute the second register of the group A for the second line of an address; while the registers 20 to 24, inclusive, constitute the third register of the group A for the third line of an address. The registers in the group B and C are arranged similarly.

A shift relay is associated with each register as 25 for the first register, 26 for the second register and 27 for the third register of the group A. 50 These shift relays are selectively energizable to close circuits from the associated register to the printing elements shown in Fig. 1, as will be described more fully hereinafter. Shift relays 28, 29 and 30 are respectively provided for the first, second and third registers of the group B and shift relays 31, 32 and 33 are respectively provided for the first, second and third registers of group C, these shift relays being similar to and for the same purpose as the shift relays 25, 26 and 27.

60 Other shift relays 106, 107 and 108 control connection of the register relays of the groups A, B and C, respectively, with the printing elements shown in Fig. 4, as will be explained.

A transfer relay as 34 is provided for each group, 65 the relay 34 being provided for the group A, the relay 35 for the group B and the relay 36 for the group C. These transfer relays are selectively energizable to close circuits from the contact bars (Fig. 3) to the register relays.

70 *Contact bars and fingers—Fig. 3*

The contact bars 37, 38 and 39 (Fig. 3) are mounted in vertical alignment and associated with each contact bar are sensing fingers as 37a, 75 37b, 37c, 37d and 37e, associated with the contact

bar 37, five such fingers being associated with each such contact bar inasmuch as the record cards or other control devices which effect operation of the illustrated machine are perforated under a five-unit code. Fingers 38a to 38e are 5 associated with the contact bar 38 and fingers 39a to 39e are associated with the contact bar 39.

Card feed—Figs. 5 and 6

A conventional card feed is illustrated in Figs. 10 5 and 6 and comprises a platform 40 on which record cards or like control devices are stacked, springs 41 acting on a backing plate 42 to urge the cards across the platform 40 toward the reciprocating card picker 43 that is mounted on a 15 crosshead 44. The crosshead 44 is slidably mounted on posts 45 and 46 and has links 47 connected thereto. The links are eccentrically connected to gears 48 fast on the shaft 49. An interrupted gear 50 is also fast on the shaft 49 20 and meshes with an interrupted gear 51 fast on the shaft 52 of the motor 53 so that whenever the motor 53 is set in operation movement is transmitted through the gear 51 to the gear 50 and thence through shaft 49 to the gears 48 whereby 25 the crosshead 44 is reciprocated on the posts 45 and 46.

The gears 48 are rotated in a counter-clockwise direction, as viewed in Fig. 5, and upon movement thereof from the position shown in Fig. 5 the link 47 causes the crosshead 44 to move downwardly whereupon the card picker 43 engages the upper edge of the adjacent card X and forces it downwardly into position between the card feed rollers 54 and 55 and 56 and 57. The rollers 54 are fast on the shaft 49 to rotate therewith and frictionally drive the rollers 55. The rollers 56, which frictionally drive the rollers 57, are fast on the shaft 58 on which gears 59 are fast that mesh with pinions 60 which in turn mesh with 40 the gears 48. Hence whenever the gears 48 are rotated the rollers 54 and 56 are rotated and these rollers frictionally drive the rollers 55 and 57.

The timing of the card feed is preferably such that in one complete revolution of the gear 51 45 three cards are fed from the platform 40, three cards being fed inasmuch as there are three groups of registers in the illustrated machine. The gears 50 and 51 are interrupted in order that a dwell will intervene between each card feeding 50 operation so that a card will remain engaged with the rollers 54 and 55 and 56 and 57 a short time prior to being fed by these rollers into a suitable card collecting tray (not shown).

The contact bars 37, 38 and 39 are associated 55 with the rollers 54 and 55 and 56 and 57 so as to lie behind the cards as they are engaged by the rollers 54 and 55 and 56 and 57 and the cards pass between the contact bars and the sensing fingers associated with such bars.

Record cards—Fig. 8

In the present instance the machine is under control of record cards such as X¹, X² and X³ (Fig. 8). Each record card has a plurality of positions Y thereon where perforations may be selectively located. Inasmuch as cards are to be perforated in accordance with a five-unit code a plurality of rows of five positions Y are provided and in the present instance four of such rows are 70 grouped longitudinally across the card. In each row record symbols for a letter, digit or other character may be accommodated and the arrangement illustrated is one, for example, which will accommodate four letters in each word. The 75

groups of four rows of positions Y extend longitudinally across the card and in the present instance where the arrangement is such that a three-line address is to be printed three rows of 5 such longitudinally extending groups are spaced transversely on the card.

In the present instance on the card X¹ a perforation P¹ is provided in the first row of the uppermost group of positions Y and in the lowermost 10 position in this row and this perforation P¹ is representative of the first character in the name line or part of an address. Also a perforation P² is provided in the first row of the middle group 15 of positions Y and in the next to the lowermost position in this row and this perforation P² is representative of the first character of the street and number line or part of an address. Furthermore, perforations P³ are provided in the first row 20 of the lowermost group of the positions Y and in the lowermost and next to lowermost positions in this row, and these perforations P³ are representative of the first character of the city and state line or part of an address.

When the record card X¹ is fed into position 25 to be engaged by the rollers 54 and 55 and 56 and 57, the perforation P¹ is aligned with the contact bar 37 and the finger 37e associated therewith, while the perforation P² is aligned with the contact bar 38 and the finger 38d associated therewith. Furthermore, the perforations P³ are aligned with the contact bar 39 and the fingers 39d and 39e associated therewith. This effects set 30 up of the register relays as will be explained more fully hereinafter.

35 *Control cams—Figs. 3 and 6*

The control cams are fast on a shaft 61 that has a gear 62 fast thereto. The gear 62 meshes with a gear 63 fast on the shaft 52 of the motor 53 40 and therefore the shaft 61 rotates in timed relation with the card feed.

In the present instance where three groups of 45 registers are provided for effecting the printing of a three-line address the control cams are arranged to effect three operations but if additional groups of registers were provided or if a less number of registers were provided the cams would be correspondingly arranged, that is to say, if there were four groups of registers the cams 50 would be arranged for effecting four operations instead of three as shown.

A cam 64 is fast on the shaft 61 and has a lobe 65 thereon that is successively engageable with the rider arms of the normally open contacts 66, 67 55 and 68 spaced equidistantly about the periphery of the cam 64. These contacts 66, 67 and 68 control energization of the transfer relays 34, 35 and 36, as will be explained.

A cam 69 is mounted on the shaft 61 adjacent 60 the cam 64 and has a lobe 70 thereon successively engageable with the rider arms of the normally open contacts 71, 72 and 73 that are spaced equidistantly about the periphery of the cam 69. These contacts 71, 72 and 73 effect operation of 65 the platens of the printing means D, E and F shown in Fig. 1, as will be explained more fully hereinafter.

Another cam 74 is fast on the shaft 61 adjacent the cam 69 and has a lobe 75 thereon successively 70 engageable with the riders of the normally open contacts 76, 77 and 78 that are spaced equidistantly about the periphery of the cam 74. These contacts 76, 77 and 78 effect operation of the sheet feed mechanism shown in Fig. 1.

75 Three cams 79, 80 and 81 are mounted in side

by side relation on the shaft 61 adjacent the cam 64 and respectively have notches 82, 83 and 84 provided in the peripheries thereof. The notches 82, 83 and 84 are respectively positioned in the cams 79, 80 and 81 in equidistantly spaced relation and the riders of the normally closed contacts 85, 86 and 87 successively move into these notches, as will be explained more fully hereinafter. The contacts 85, 86 and 87 control the holding and releasing of the register relays (Fig. 2).

Three cams 88, 89 and 90 are mounted on the shaft 61 in side by side relation adjacent the cams 79, 80 and 81 and have elongated lobes or dwells 91, 92 and 93 respectively provided on the peripheries thereof, said lobes being respectively located on the cams to be equidistantly spaced one from the other. These lobes are successively engageable with the riders of the normally open contacts 94, 95 and 96 which selectively control contacts 25 to 33, inclusive, of Fig. 2, as will be explained.

Grounding of the contact bars 37, 38 and 39 is under control of the cam 97 fast on the shaft 61 adjacent the cam 98 and having a lobe 98 thereon successively engageable with the riders of the normally open contacts 99, 100 and 101.

Another cam 102 is fast on the shaft 61 and has an elongated lobe 103 thereon that is successively engageable with the riders of the normally open contacts 104, 105 and 106' equidistantly spaced about the periphery of cam 102. These contacts 104, 105 and 106' respectively control the shift relays 106, 107 and 108 (Fig. 2).

Another cam 109 is fast on the shaft 61 adjacent the cam 102 and has a lobe 110 thereon successively engageable with the riders of the normally open contacts 111, 112 and 113 that control the platens of the printing means L, M and N (Fig. 4), as will be explained more fully hereinafter.

35 *Printing element—Fig. 7*

The printing element illustrated in Fig. 7 is typical of that employed in each of the printing means of this machine and consists of a type bar 114 carrying type members as 115 that are selectively movable into printing position below a platen 116 that is under control of the electromagnet 117 which, when energized, attracts the platen against the action of the spring 118. When the electromagnet is deenergized platen 116 is snapped downwardly by said spring 118 to make an impression on a sheet disposed below the ink ribbon R, the impression being made through the ribbon from the one of the type members 115 that is selectively positioned below said platen. A pin 119 is provided to limit movement of the platen 116 under the action of the spring 118.

A spring 120 acts on the type bar 114 to normally position this bar that all of the type members as 115 are out of printing position below the platen 116. A conventional permutation movement is shown in Fig. 7 for selectively positioning the type members 115 below the platen 116.

The permutation movement illustrated herein is one adapted for use in connection with a five-unit code inasmuch as the record cards used herein are perforated under such a code. In the illustrated form this permutation movement includes five permutation members 121, 122, 123, 124 and 125, each of which has a different length of stroke for displacing the type bar 114 a given

5

55

60

65

70

75

spacing against the action of the spring 120. Thus the member 121 will displace the bar 114 one space; the member 122 two spaces; the member 123 four spaces; the member 124 eight spaces; 5 and the member 125 sixteen spaces. Through the action of these members singly or in combination the type bar 114 may be selectively moved from one to thirty-one spaces to thereby selectively position any one of the thirty-one type 10 members 115 on the type bar 114 below the platen 116. It will be understood that the spacing of the type members 115 one from the other and the spacing of the first type member from the platen 116 when in operative position is equal to one 15 unit of the spacing movement imparted to the type bar 114 by permutation members 121 to 125, inclusive.

The permutation members in the present instance are operated by solenoids, solenoids 126 to 20 130 being respectively associated with the permutation members 121 to 125. Each permutation member also includes a plunger rod as 127', two slide bars as 128' and 129', a spacing bar as 130' and a push bar as 131. In order to insure that the 25 movement of the permutation members will effect the desired movement of the type bar 114 a fixed member 132 is provided at the end of the unit opposite that end at which the type bar 114 is positioned.

30 If the solenoid 126 is energized the plunger rod 127' will be forced downwardly whereby the push bar 131 will be actuated to move the type bar 114 one space. If, for example, the solenoids 126 and 128 are energized, the push bar 131 and the push 35 bar associated with the permutation member 123 will be actuated whereby the type bar 114 will be moved five spaces inasmuch as the permutation member 121 imparts a movement equivalent to one space and the permutation member 123 im- 40 parts a movement equivalent to four spaces. Selective energization of one or more of each of the solenoids in this manner selectively imparts the proper degree of movement to the type bar 114 to selectively position the type bars 115 below 45 the platen 116.

The solenoids, that is to say permutation members, are under control of the register relays and the selective energization of the register relays, in a manner explained more fully hereinafter, 50 effects selective energization of the solenoids and therefore selective positioning of the type members. Hence by positioning the type members in accordance with the system under which the registers are selectively energized the positioning 55 of the type members will correspond to the selective energization of the register relays.

Line by line printer—Fig. 1

In Fig. 1 I have illustrated the arrangement 60 of three printing means of the kind shown in Fig. 7. These printing means D, E and F are arranged in endwise alignment and are for the purpose of effecting the printing of the first character of each line of a three-line address. Thus 65 a platen 116a of the printing means B is provided for selectively making impressions from the type members 115b on the type bar 114b to print the first character in the first line of an address. The platen 116b of the printing means E is pro- 70 vided to selectively make impressions from the type members 115b on the type bar 114b to print the first character of the second line of an address. The platen 116c of the printing means F is pro- 75 vided to selectively make impressions from the type members 115c on the type bar 114c to make

an impression for the first character of the third line of an address.

The printing means D, E and F are illustrative of means for printing the lines of an address, other similar means being associated with these 5 means to print the other characters in the line. Since such other means are merely duplicates of the means D, E and F, only the means D, E and F are shown for the sake of simplicity.

Sheet feed—Fig. 1

10

The sheet feed shown in Fig. 1 includes an endless conveyor such as a belt 133 directed about pulleys 134 and 135 spaced apart sufficiently to permit sheets carried by the conveyor 133 to be 15 selectively positioned in the printing means D, E and F.

A step by step movement is imparted to the conveyor 133 through sprockets as 136 fast on the shaft 137 having a pinion 138 fast thereon 20 that meshes with a gear 139 rotatable on the shaft 140. A ratchet 141 rotatable on shaft 140 is fixedly connected to gear 139 and is engaged by the spring-pressed retaining pawl 142. An arm 143 fast on the shaft 140 carries a spring-pressed 25 pawl 144 engageable with the ratchet 141. A link 45 is connected to the arm 143 and is attached to the plunger 146 of the solenoid 147. The solenoid 147 is energized under control of the contacts 76, 77 and 78 and when energized attracts 30 its plunger 146 which therefore moves the link 145 to the right as viewed in Fig. 1, and this movement is imparted through the arm 143, pawl 144, ratchet 141, gear 139, pinion 138 and sprocket 136 to the conveyor 133 whereby the conveyor 35 is moved clockwise as viewed in Fig. 1. Upon deenergization of the solenoid 147 the spring 148 returns the plunger 146 and arm 145 whereupon the pawl 144 freely rides over the teeth of the ratchet 141 and the pawl 142 retains the ratchet 40 in its advance position.

On the conveyor 133 are sheet engaging ledges 45 as 149 which are equidistantly spaced one from the other and each time movement is imparted to conveyor 133 sheets engaged by selected of the ledges are moved from position below one of the platens into position below the next platen to the right or are discharged from the machine.

The platens of the printing means D, E and F, however, are not equidistantly spaced from each other but, for example, the platen 116b is spaced from the platen 116a in an amount equal to the spacing between adjacent ledges 149 on the conveyor 133 plus the desired spacing between the first and second lines of the address. Likewise, 50 the platen 116c is spaced from the platen 116b in an amount equal to the spacing between adjacent ledges 149 and the desired spacing between the second and third lines of an address. Hence when a sheet engaged by one of the ledges 149 55 is first moved into association with the platen 116a it receives an impression in the top line of an address and then when moved into association with the platen 116b it receives an impression in the second line of an address, and when subsequently moved into association with the platen 116c it receives an impression in the third line of an address. Such spacing of the platens one from the other will be carried out if additional printing 60 positions are provided as where a four-line address is to be printed.

Straight line printer—Fig. 4

Printing elements D, E and F (Fig. 1) are arranged in endwise alignment and are spaced apart 75

to effect printing in different lines of an address but the printing elements L, M and N of Fig. 4 are arranged in side by side relation and are spaced apart to effect printing in a single line. 5 The printing elements L, M and N are similar to that shown in Fig. 7 and respectively include platens 116d, 116e and 116f which respectively and selectively make impressions from type members 115d, 115e and 115f that are respectively 10 carried by type bars 114d, 114e and 114f. The platens 116d, 116e and 116f are respectively under control of electromagnets 117d, 117e and 117f that are under control of the contacts 111, 112 and 113 of the cam 109, as will be explained more 15 fully hereinafter.

The platen 116d is adapted to print the first character of the first line or part of an address, the platen 116e the first character of the second line or part of an address and the platen 116f 20 the first character of the third line or part of an address. These platens are spaced one from the other a distance sufficient to enable the required number of printing elements for printing the desired number of characters in each line or 25 part of an address to be accommodated in side by side relation.

Sheet feed—Fig. 4

An endless conveyor 150 is provided which 30 has a ledge 151 thereon that engages one end of a sheet on which impressions are to be made in side by side relation of the three lines or parts of the addresses. This sheet is moved through the machine in a step by step manner so that the lines of impressions made thereon will be 35 spaced one from the other. To this end the conveyor is directed about sprockets as 152 fast on a shaft 153 having a ratchet 154 thereon engaged by a pawl 155 urged in one direction by a spring 156 and movable in the other direction by 40 an electromagnet 157. The electromagnet is under control of contacts in the shift relays 106, 107 and 108, as will be explained more fully hereinafter, and when energized actuates the pawl 155 which acts on the ratchet 154 to move the shaft 153 and the sprockets 152 so that the conveyor 150 and therefore ledge 151 thereon and the sheet 45 engaged by this ledge are moved sufficiently to space one line impression from the next line impression.

Entry of record in register relays

Assuming that the card X¹ has been fed into 55 position over the contact bars 37, 38 and 39 and that the motor 53 is in operation, immediately after card X¹ comes to rest over the contact bars, the rotation of the cam shaft 61 will move the lobe 65 on the cam 64 into the position shown to close the normally open contact 66 whereby ground is applied to the transfer relay 34 to energize it through the conductor 158 (Fig. 2), 158 (Fig. 3), that interconnects the contact 66 and relay 34. (The transfer relay 34 is shown de-energized notwithstanding the showing of contact 66 closed to facilitate illustration.)

Likewise the lobe 98 on the cam 97 closes the 65 normally open contact 99 thereby grounding conductors 159 and 160 whereby the contact bars 37, 38 and 39 are grounded. Inasmuch as the card X¹ is above the contact bars the perforation P¹ 70 will be aligned with the sensing finger 37e which will pass through this perforation and be grounded on the bar 37. Also the sensing finger 38d will pass through the perforation P² and be 75 grounded on the bar 38. Furthermore the sens-

ing fingers 38d and 39e will pass through the perforations P³ and be grounded on the bar 39.

A conductor 161 (Fig. 3), 161 (Fig. 2), leads from the finger 37e to the contact 162 in the transfer relay 34. A conductor 163 (Fig. 3), 163 (Fig. 2), leads from the finger 38d to the contact 164 in the transfer relay 34. A conductor 165 (Fig. 3), 165 (Fig. 2), leads from the sensing finger 39d to the contact 166 in the transfer relay 34 while a conductor 167 (Fig. 3), 167 (Fig. 2), 10 leads from the sensing finger 38e to the contact 168 in the transfer relay 34. Inasmuch as the transfer relay 34 is energized by the closing of now closed contact 66 the contacts 162, 164, 166 and 168 are closed at this time.

A conductor 169 leads from the contact 162 to the winding 14a of the relay 14 that is connected to the battery 170 through a conductor 171 wherefore relay 14 is energized inasmuch as contact 162 is grounded through conductor 161 and sensing finger 37e and grounded contact bar 37. A conductor 172 leads from contact 164 to winding 18a of relay 18 which is connected to the battery 170 and therefore relay 18 is energized. A conductor 173 leads from contact 166 to winding 23a of relay 23 which is connected to the battery 170 and therefore relay 23 is energized. A conductor 174 interconnects contact 168 and winding 24a of relay 24 that is connected to the battery 170 wherefore relay 24 is energized.

All of the register relays have two windings one of which windings, as the winding 14a, is connected to a contact in the transfer relay for the group in which the register relay is included. The other winding as 14b is connected to a contact as 14c that is closed when the register relay is energized. Thus the left hand windings of the register relays shown in Fig. 2 are initial energizing windings while the right hand windings are holding windings for maintaining the relays 40 energized.

Thus when the winding 14a of the relay 14 was energized contact 14c was closed. The winding 14b like the winding 14a is connected to the battery 170 through the conductor 171. 45 Contact 14c as well as every other like contact in the first row of register relays in the group A is connected to a conductor 175 (Fig. 2), 175 (Fig. 3), that is connected to a contact in the normally closed and grounded multiple contact 85 associated with the cam 79. Likewise when the winding 18a of the relay 18 was energized, contact 18c thereof was closed whereby winding 18b, connected to the battery 170 thereof was grounded through conductor 176 (Fig. 2), 176 (Fig. 3), 55 that is connected to a contact in the normally closed and grounded multiple contact 86 associated with the cam 80. The contact 18c and every other like contact in the second row of register relays in the group A is connected to the conductor 176. Furthermore, when the winding 23a of the relay 23 was energized contact 23c was closed, this contact being connected to the winding 23b of the relay 23 and the contact 24c of the relay 24 connected to the winding 24b of this relay was also closed when the relay 24 was energized. The windings 23b and 24b are both connected to the battery 170. The contacts 23c and 24c and every like contact in 60 the third row of registers in the group A are connected to a conductor 177 (Fig. 2), 177 (Fig. 3), that is connected to a contact in the normally closed and grounded multiple contact 87 associated with the cam 81 and therefore closing of 65

70 the third row of registers in the group A are connected to a conductor 177 (Fig. 2), 177 (Fig. 3), that is connected to a contact in the normally closed and grounded multiple contact 87 associated with the cam 81 and therefore closing of 75

the contacts 23c and 24c energizes the windings 23b and 24b.

Thus whenever selected register relays are energized in accordance with perforations in a 5 card associated with the contact bars 37, 38 and 39, these relays are locked up under control of contacts associated with the cams 79, 80 and 81.

Shortly after the register relays are locked up the lobe 65 disengages the contacts 66 and the 10 lobe 98 disengages the contact 99 and therefore the transfer relay 34 is deenergized and ground is removed from the contact bars 37, 38 and 39. At this time, however, the multiple contacts 85, 86 and 87 remain closed so that the register re- 15 lays which were locked up remain energized.

The card X¹ is then fed from association with the contact bars 37, 38 and 39 and the card X² is fed into association with these bars. The card X² is so perforated that the sensing fingers 31d, 20 38d, 38e and 39e will pass through perforations therein and be grounded on their associated contact bars 37, 38 and 39, these contact bars being grounded at the time card X² is positioned thereabove by the engagement of the lobe 98 with the 25 contact 101 to close said contact and thereby ground the conductors 159 and 160 and consequently the contact bars. At this same time the lobe 65 will engage the contact 66 whereby the conductor 178 (Fig. 3), 178 (Fig. 2), will be 30 grounded to effect energization of the transfer relay 35.

By referring to Fig. 2 it will be noted that the conductors leading from the sensing fingers are multiplied to contacts in the transfer relays 34, 35 and 36 and it has been explained that when the transfer relay 34 was energized the grounded sensing fingers were connected to certain of the contacts of the transfer relay 34 and that these contacts in turn were respectively connected to 40 register relays in the group A. This is also true with respect to the contacts of the transfer relays 35 and 36, the contacts of which relays are respectively connected to the register relays in the groups B and C.

45 Thus inasmuch as transfer relay 35 is energized at this time the contacts thereof are closed. Hence the sensing finger 31d effects energization of the relay 179 in the first row of register relays in the group B. Likewise 50 the sensing fingers 38d and 38e effect energization of the relays 180 and 181 in the second row of register relays in the group B and the sensing finger 39e effects energization of the register relay 182 in the third row of register relays 55 in the group B.

The contact 179c of the register relay 179 and all like contacts associated with the register relays in the first row of the group B are connected to a conductor 183 (Fig. 2), 183 (Fig. 3), and 60 this conductor is connected to a contact in the normally closed and grounded multiple contact 86 associated with the cam 80. The contacts 180c and 181c of the relays 180 and 181 and all like contacts associated with register relays in 65 the second row in the group B are connected to a conductor 184 (Fig. 2), 184 (Fig. 3), that is connected to a contact in the normally closed and grounded multiple contact 87 associated with the cam 81. The contact 182c of the relay 70 182 and all like contacts associated with the register relays in the third row in the group B are connected to a conductor 185 (Fig. 2), 185 (Fig. 3), that is connected to a contact in the normally closed and grounded multiple contact 85 75 associated with the cam 79.

The contacts 179c, 180c, 181c and 182c are connected to the holding windings of the relays with which they are associated, and under control of the multiple contacts associated with the cams 79, 80 and 81 hold the relays in the group B 5 energized after the lobe 65 disengages the contact 66 and the lobe 98 disengages the contact 101, which occurs shortly after energization of the register relays in the group B.

After the card X² has effected energization of the register relays of the group B this card is fed from association with the contact bars 37, 38 and 39 and the card X³ moves into association with these contact bars. After this card is positioned above the bars the lobe 65 engages the contact 67 which through the conductor 186 (Fig. 3), 186 (Fig. 2), is connected to the transfer relay 36 wherefore the transfer relay 36 is energized. Likewise the lobe 98 engages the contact 100 to ground the conductors 159 and 160 and the 20 contact bars 37, 38 and 39.

By referring to Fig. 8 it will be noted that the card X³ is so perforated that the fingers 31d and 31e will be grounded as will the sensing fingers 38d and 39e. These fingers, as explained, are 25 connected to contacts in the transfer relay 36 which in turn are respectively connected to register relays in the group C. Hence the grounded sensing fingers will effect energization of the relays 187 and 188 in the first row of register relays in the group C, the register relay 189 in the second row of relays in the group C, and the register relay 190 in the third row of the group C. 30

The contacts 187c and 188c of the relays 187 and 188 and all like contacts associated with the register relays in the first row of the group C are connected to a conductor 191 (Fig. 2), 191 (Fig. 3), that is connected to a contact in the normally closed and grounded multiple contact 87 associated with the cam 81. The contact 189c 40 associated with the relay 189 and all like contacts associated with the register relays in the second row of the group C are connected to a conductor 192 (Fig. 2), 192 (Fig. 3), that is connected to a contact in the normally closed and grounded multiple contact 85 associated with the cam 79. The contact 190c of the relay 190 and all like contacts associated with register relays in the third row of the group C are connected to a conductor 193 45 (Fig. 2), 193 (Fig. 3), that is connected to a contact in the normally closed and grounded multiple contact 86 associated with the cam 80. 50

The contacts 187c, 188c, 189c and 190c are respectively connected to the holding windings of the relays with which they are associated and maintain these relays energized so long as the multiple contacts associated with the cams 79, 80 and 81 remain closed. Subsequent to energization of the relays in the group C the lobe 65 55 disengages the contacts 67 and the lobe 98 disengages the contact 100 wherefore the transfer relay 36 is deenergized and ground is removed from contact bars 37, 38 and 39.

It will be noted that during the passage of the first three cards through the machine register relays in the groups A, B and C were respectively energized and, as has been explained, this is an arrangement for printing a three-line address. If a four-line address is to be printed the cards 65 would be equipped with a fourth transversely spaced group of perforations Y and a fourth group of register relays would be provided, and if this arrangement is utilized this fourth group 70 of register relays will be energized and held en- 75

5 energized in the manner above described after energization of the relays in the third group. However, inasmuch as the present arrangement is such that a three-line address is printed, the above described energization of register relays in the groups A, B and C occurs during one complete revolution of the shaft 61.

10 After the third card X³ has passed from association with the contact bars 37, 38 and 39, the fourth card moves into association therewith. By this time, as will be explained more fully hereinafter, the register relays of the group A will all be released and the perforations in the fourth card will selectively effect energization 15 of the register relays in the group A. Furthermore, the fifth card will effect energization of the register relays of the group B, the sixth card the register relays of the group C, the seventh card the register relays of the group A and so on.

20 *Set-up of the line by line printer—Fig. 1*

One of the important objects of the present invention is to enable the lines of a multiple line address to be printed separately as rapidly 25 as printing could be effected if all lines were printed simultaneously. This object is attained by printing one line of each address in each printing operation of the machine. Thus in the present instance where a three-line address is 30 to be printed three printing means D, E and F are provided. The printing means D always prints the first line of an address of a three-line address, the printing means E the second line, and the printing means F the third line. The 35 sheets or the like receiving these impressions are successively passed from one of these printing means to the other intermediate printing operations and receive an impression in each printing means and therefore a complete three-line address is printed in each printing operation of the machine.

It will be noted from the description of the entry of records in the register relays that the first line of an address is always entered in the 45 first row of a group of register relays, the second line of an address in the second row of register relays and the third line of an address in the third row of register relays. Hence I provide means which in each of the three phases of a 50 single cycle of operation of the machine selectively connect the rows of register relays to the proper printing element, and such means includes the shift relays 25 to 33, inclusive, that are under control of the cams 88, 89 and 90.

55 Hence a conductor 194 (Fig. 3), 194 (Fig. 2), is connected to the contact 94 associated with the cam 88 and to shift relay 25. A conductor 195 (Fig. 3), 195 (Fig. 2), is connected to the contact 95 associated with the cam 89 and to shift 60 relay 26. A conductor 196 (Fig. 3), 196 (Fig. 2), is connected to the contact 96 associated with the cam 90 and to shift relay 27. These conductors are also respectively multiplied to the proper shift relays, as will now be explained.

65 A conductor 197 (Fig. 3), 197 (Fig. 2), leads from the conductor 194 to the shift relay 32. A conductor 198 (Fig. 3), 198 (Fig. 2), leads from the conductor 194 to shift relay 30. The conductor 194 (Fig. 3), 194 (Fig. 2), terminates in 70 the shift relay 25. A conductor 199 (Fig. 3), 199 (Fig. 2), leads from the conductor 195 to the shift relay 33. A conductor 200 (Fig. 3), 200 (Fig. 2), leads from the conductor 195 to the shift relay 28. A conductor 201 (Fig. 3), 201 (Fig. 2), 75 leads from the conductor 196 to the shift relay

31. A conductor 202 (Fig. 3), 202 (Fig. 2), leads from the conductor 196 to the shift relay 29.

It will thus be seen that the cam 88 and its contact 94 control the shift relay 25 for the first row in the group A, the shift relay 30 for the 5 third row in the group B, and the shift relay 32 for the second row in the group C. Likewise, the cam 89 and its contact 95 control the shift relay 28 for the first row in the group B, the shift relay 33 for the third row in the group C, and 10 the shift relay 26 for the second row in the group A. Furthermore, the cam 90 and its contact 96 control the shift relay 31 for the first row in the group C, the shift relay 27 for the third row in the group A, and the shift relay 29 for the 15 second row in the group B. Each group of shift relays under control of a particular cam will be closed simultaneously and the records entered in the respective rows of relay registers associated with these shift relays will be simultaneously 20 transferred to the printing elements, as will now be explained.

Each of the register relays includes a contact as 14d and each of the contacts as 14d in each row in each of the groups of register relays is connected to a common conductor as 203 for the contacts as 14d in the first row in the group A. These common conductors as 203 are connected to a grounding contact as 204 in the shift relay as 25 for the row of register relays. Likewise each contact as 14d is individually connected by a conductor as 205 to a contact as 206 of the shift relay as 25 associated with the respective rows.

When relay 14 is energized contact 14d is closed and when shift relay 25 is energized contact 204 is closed whereby through conductor 203 contact 14d is grounded and likewise contact 206 is grounded through conductor 205. Each contact as 206 is connected by a conductor as 207 (Fig. 2), 40 207 (Fig. 1), to the winding of a solenoid as 126a of the printing means D; each solenoid also being connected to the battery 208. Hence when shift relay 25 is energized and contact 206 is grounded solenoid 126a is energized whereupon the type bar 114a is moved one space, as explained heretofore. 45

In a manner such as that just explained the contacts 13d, 12d, 11d and 10d of the register relays in the first row in the group A are connected to the conductor 203 and also respectively 50 to contacts in the shift relay 25. These other contacts in the shift relay 25 are respectively connected by conductors to the other solenoids of the printing element of the printing means D. Thus depending upon which ones of the register 55 relays 10 to 14 are energized the energizing of the shift relay 25 effects energization of the solenoids of the printing element of the printing means D.

The shift relay 26 when energized selectively 60 effects energization of the solenoids of the printing element of the printing means E depending upon which of the relays 15 to 19 are energized and likewise the shift relay 27 similarly selectively effects energization of the solenoids of 65 the printing element of the printing means F. From the above description it will be apparent that the shift relay 25 for the first row in the group A when energized connects the contacts, similar to the contact 14d, of the energized register relays in the first row with the first printing means D, that the shift relay 26 connects the contacts, similar to the contact 14d, of the energized register relays of the second row of the group A with the second printing means E, and 70 75

that the shift relay 27 connects the contacts, similar to the contact 14d, of the energized register relays of the third row of the group A with the third printing means F. The shift relays 28, 29 and 30 for the first, second and third rows of register relays of the group B likewise selectively connect the contacts, similar to the contact 14d, of the energized register relays of these rows respectively with the printing elements D, E and F when these relays 28, 29 and 30 are energized and the shift relays 31, 32 and 33 likewise function for the register relays of group C.

Thus when the register relay 18 is energized, energizing of the shift relay 26 will effect energization of the solenoid 127b of the printing means E whereby the second type member 115b on the type bar 114b will be moved into printing position. Likewise when the register relays 28 and 29 are energized the solenoids 126c and 127c 20 will be energized, and since the combined movement imparted under control of the solenoids 126c and 127c is three spaces the third of the type members 115c will be disposed in printing position upon energization of the shift relay 27. 25 However, the shift relays 25, 26 and 27 are not energized simultaneously since energization of the shift relays, as has been explained, is under control of the cams 88, 89 and 90 which operate successively rather than simultaneously to close contacts 94, 95 and 96. The lobes or dwells 91, 92 and 93 on the cams 88, 89 and 90 are relatively elongated so that when the contacts 94, 95 and 96 are closed the shift relays energized as a result of this closing are maintained for a 30 sufficient period of time to permit set-up of the printing elements of the printing means D, E and F and the making of impressions from the set-up printing elements.

Release of locked-up register relays

The printing elements D, E and F are first simultaneously set up under control of the shift relays 25, 32 and 30, next under control of the shift relays 28, 26 and 33, and then under control 45 of the shift relays 31, 29 and 27. This is under control of the cams 88, 89 and 90. The cams 79, 80 and 81 operate in timed relation to the cams 88, 89 and 90 and it is the cams 79, 80 and 81 that effect holding energized the register relays under control of the multiple contacts 85, 86 and 87 respectively associated with the cams 79, 80 and 81. Hence because of the timed 50 relation between the cams 88, 89 and 90 and 79, 80 and 81 the held register relays may be released in timed relation to the printing after setting up the printing elements of the printing means D, E and F under control of the shift 55 relays.

Thus the conductor 175 for the register relays in the first row of the group A, the conductor 185 for the register relays in the third row in the group B and the conductor 192 for the second row of register relays in the group C are connected to the contact 85. The conductor 183 for the first row in group B, the conductor 193 for the third row in the group C and the conductor 176 for the second row in the group A are connected to the contact 86, and the conductor 191 for the first row in group C, conductor 177 for the third row in the group A and the conductor 184 for the second row in the group B are connected to the contact 87.

The cams 79, 80 and 81 have the notches 82, 83 and 84 therein. These notches are respectively so positioned that, immediately after the

dwell 91 on the cam 88 has disengaged the contact 94 to thereby deenergize the shift relays under control thereof, the notch 82 in the cam 79 permits the contact 85 to open whereby the register relays energized in the first row in the group A, the third row in the group B and the second row in the group C are deenergized. Likewise after the dwell 92 has permitted the contact 95 to open the notch 83 permits the contact 86 to open whereby the register relays locked up in the first row of the group B, the third row of the group C and the second row of the group A are released. Furthermore, when the dwell 93 permits the contact 96 to open the register relays in the first row in the group C, the third row in the group A and the second row in the group B are deenergized. It will therefore be seen that the release of the locked-up register relays in a particular row immediately follows deenergization of the shift relay for the particular row.

Impression operations—line by line printing

The electromagnets 117a, 117b and 117c which respectively control operation of the platens 116a, 116b and 116c of the printing means D, E and F 25 are each connected to a battery and to a grounding conductor 208 (Fig. 1), 208 (Fig. 3), that is connected to the conductor 209 that interconnects the contacts 71, 72 and 73.

Prior to the time the lobe or dwell 91 disengages contact 94, the lobe 70 engages the contact 73 and closes it whereupon the conductors 209 and 208 are grounded which energizes the electromagnets 117a, 117b and 117c and immediately thereafter and just prior to the time the lobe 91 disengages the contact 94 the lobe 70 disengages the contact 73 whereupon the electromagnets 117a, 117b and 117c are freed from ground and deenergize. Thereupon the springs 118a, 118b and 118c snap the platens 116a, 116b 40 and 116c downwardly to make impressions on the sheets carried by the conveyor 133 and positioned below the respective type members 115a, 115b and 115c which will have been previously selectively positioned relative to the platens.

The lobe 70 closes and opens the contacts 72 relative to the operation of the contact 95 by the lobe or dwell 92 and likewise the lobe 70 opens and closes the contacts 71 relative to the operation of the contact 96 by the lobe or dwell 93 50 in the same timing as that described above in connection with the operation of the contact 73 by the lobe 70 relative to the operation of the contact 94 by the dwell or lobe 91.

Sheet feed—line by line printing

Immediately after the lobe 70 disengages the contact 73 the lobe 75 on the cam 74 closes the contacts 78 whereupon the conductors 211 and 210 (Fig. 3), 210 (Fig. 1), are grounded. The conductor 210, as shown in Fig. 1, is connected to the solenoid 147 which is also connected to the battery 212 wherefore grounding of the conductor 210 effects energization of the solenoid 147 with the effect of advancing the conveyor 65 133 in the manner previously explained. Since the lobe 75 does not close the contact 78 until after the lobe 70 has disengaged the contact 73 the sheet feed is not operated until after an impression has been made by the platens of the 70 printing elements D, E and F.

The lobe 75 successively closes the contacts 76 and 77 to effect energization of the solenoid 147 subsequent to the disengagement of the lobe 70 from the contacts 72 and 71 in the same timed 75

relation as that above described relative to the operation of the contacts 18 by the lobe 75 and it will thus be seen that in each cycle of operation the conveyor 133 is advanced three times, once for each phase of each cycle of operation.

The set-up of straight line printer—Fig. 4

It has been explained that energization of the shift relays 25 to 33 is followed by deenergization of the register relays in the row with which the shift relay is associated and it has also been explained that the shift relays have the effect of transferring the records entered in the register relays to the line by line printing means D, E and F. Furthermore, it has been explained that the shift relays 25 to 33 are so arranged that only one shift relay for each group of register relays is energized for each printing operation of the printing means D, E and F with the result that only one part of the record from a particular card is printed in each phase of a cycle of operation.

It may be advantageous, however, to print all parts of a record entered in a group of register relays at one time as where a list is being prepared. The straight line printer shown in Fig. 4 is adapted for such operation. Thus, the shift relays 106, 107 and 108 are provided for the purpose of transferring the entire record entered in the group of register relays with which they are respectively associated to the printing elements of the printing means L, M and N in a single phase of operation, and these printing elements thereupon print the entire record entered in one group of register relays in a single phase of a cycle of operation.

Thus in the group A a conductor 213 is connected to the conductor 205 leading from the contact 14d and this conductor 213 leads to the contact 214 in the shift relay 106. Conductors similar to the conductor 213 are connected to each of the conductors similar to the conductor 205 and respectively connect the conductors like 205 to contacts like the contact 214 in the shift relay 106 so that in the group A every conductor like the conductor 205 is connected to a contact in the shift relay 106 like the contact 214 wherefore each contact as 14d that is closed grounds contact as 214 whenever a shift relay as 106 is energized. To this end a grounding contact as 215 is associated with each shift relay as 106. A conductor as 216 leads from the grounding contact as 215 to the conductors as 203 that are common to the contacts as 14d in each row of the group with which the shift relay as 106 is associated. By reason of this interconnection of the common conductors as 203 in each of the rows, all closed contacts as 14d are also energized each time a shift relay as 25 is energized but this is without effect inasmuch as the other shift relays associated with the other rows of the group are not simultaneously closed.

Energization of shift relay 106 and the closing of grounding contact 215 grounds all closed contacts as 14d in the group A which through their conductors as 205 and 213 ground contacts as 214 in the shift relay as 106. Contacts as 214 are connected through conductors as 217 (Fig. 2), 217 (Fig. 4), with solenoids as 126d of the printing elements of the printing means L, M and N.

Inasmuch as contact 18d of relay 18 is closed solenoid 127e of the printing element of the printing means M will be closed upon the energization of relay 106 and likewise since contacts 23d and 24d are closed solenoids 126f and 127f of the

printing element of the printing means N will be energized upon the energization of shift relay 106.

A conductor 218 (Fig. 2), 218 (Fig. 3), leads from shift relay 106 to contact 106' associated with cam 102. A conductor 219 (Fig. 2), 219 (Fig. 3), leads from shift relay 107 to contact 106 associated with cam 102 while a conductor 220 (Fig. 2), 220 (Fig. 3) leads from shift relay 108 to contact 106 associated with cam 102. The contacts 106', 105 and 104 are positioned about the cam 102 relative to the location of the lobes 91, 92 and 93 about the cams 88, 89 and 90 and the lobe 103 is positioned on the cam 102 to close the contacts 106', 105 and 104 respectively and simultaneously with the closing of the contacts 94, 95 and 96.

It will be remembered that the contact 94 effects energization of the shift relay 25 for the first row in the group A, the closing of the contact 95 effects energization of the shift relay 28 for the first row in the group B and the closing of the contact 96 effects energization of the shift relay 31 for the first row in the group C. The arrangement is such that the lobe 103 engages the contact 106' to effect energization of the shift relay 106 simultaneously with the energizing of the shift relay 25 and likewise lobe 103 closes contact 105 to effect energization of shift relay 101 simultaneously with the energization of the shift relay 28 while the lobe 103 closes the contact 104 to effect energization of the shift relay 108 simultaneously with the energization of the shift relay 31. It will thus be seen that the first line or part of each record entered in a group of register relays will be printed simultaneously in the printing elements of the printing means D and L. However, simultaneously with the printing of the first part or line of a record in the printing means L the second and third parts will be printed in the printing means M and N, but the second and third parts of the record are not printed by printing means E and F until subsequent phases of the cycle of operation. It will thus be apparent that at least a part of each record is printed simultaneously at two different places in the first phase of each cycle of operation of the machine.

Impression operation—straight line printing

The contacts 111, 112 and 113 are respectively connected to a conductor 221 to which a conductor 222 (Fig. 3), 222 (Fig. 4), is connected and this conductor is connected to the electromagnets 111d, 111e and 111f of the printing means L, M and N, respectively, which electromagnets are each connected to a battery. The lobe 110 on the cam 109 successively closes the contacts 111, 112 and 113 simultaneously and respectively with the closing of the contacts 73, 72 and 71 whereby the platens 116d, 116e and 116f operate simultaneously with the platens 116a, 116b and 116c.

Sheet feed—straight line printing

Each shift relay as 106 includes a grounding contact as 223. The conductor 224 (Fig. 2), 224 (Fig. 4), is connected to each of these grounding contacts and leads to the electromagnet 157 that is connected to a battery. Thus each time the shift relay as 106 is energized a contact as 223 is closed and the electromagnet 157 is energized. The energization of the electromagnet 157 causes pawl 155 to act on the teeth of ratchet 154 to thereby so rotate the

shaft 153 that the sheet engaged with the ledge 151 on said conveyor 150 is advanced the desired spacing between the impressions made thereon, this arrangement affording what is known as line spacing. Upon deenergization of a shift relay as 106 and consequent opening of the grounding contact as 223 thereof, conductor 224 is freed from ground whereby electromagnet 157 deenergizes and spring 156 engages the pawl 155 with a tooth on the ratchet 154 to the rear of the tooth previously engaged by the pawl. Thus since a shift relay as 106 is energized each time the printing means L, M and N make an impression and as the energization of the shift relay as 106 causes the advance of the sheet on which such impressions are made it is apparent that the impressions made by the printing means L, M and N are properly spaced one from the other.

20

Operation

A stack of cards is disposed on the platform 40 and in the present instance cards X¹, X² and X³ are arranged to be fed in succession one after the other by the picker 43. The first sheet S¹ on the conveyor 133 is engaged with a ledge 149 and is positioned in the printing means D. The ledge 151 on the conveyor 150 is disposed so that the top line of the sheet SS to receive impressions in the printing means L, M and N is one space out of printing position in these printing means. The card X¹ is fed into position over the contact bars 37, 38 and 39. The motor 53 is then set in operation.

35

First phase—first cycle

Immediately after the motor 53 is set in operation the cams 97 and 64 move into the position illustrated in Fig. 3 whereupon the contacts 99 and 66 are closed and ground is applied to the contact bars 37, 38 and 39 and the transfer relay 34 is energized. By reason of the location of the perforations in the card X¹ and in the manner previously described, the register relays 14, 18, 23 and 24 are energized and locked up. Inasmuch as the shaft 61 is rotating the lobe 65 will disengage the rider of contact 66 and the lobe 98 will disengage the rider of contact 99 and these contacts will open shortly after the register relays 14, 18, 23 and 24 are energized. Opening of the contacts 66 and 99 deenergizes transfer relay 34 and removes ground from the contact bars 37, 38 and 39.

Shortly after the disengagement of lobes 65 and 98 from the riders of contacts 66 and 99 the lobe 91 engages the rider of contact 94 and closes this contact. This energizes shift relays 25, 30 and 32 but in this phase of this cycle of operation the energization of shift relays 30 and 32 is without effect inasmuch as no register relays in the groups B and C are locked up. However, the closing of shift relay 25 effects energization of the solenoid 126a of the printing element of the printing means D, with the resultant positioning of the selected type member 115a.

Simultaneously with the engagement of the lobe 91 with the rider of contact 94, lobe 103 engages the rider of contact 106' whereupon shift relay 106 is energized simultaneously with the energization of shift relay 25. The energization of shift relay 106 connects the contacts as 14d of the locked-up register relays of the group A with the solenoids of the printing elements of the printing means L, M and N whereupon the sole-

noids 126d, 127e, 126f and 127f are energized to position the selected of the type members 115d, 115e and 115f in printing position.

Upon the energization of shift relay 106 grounding contact 223 is closed whereupon electromagnet 157 is energized to advance the conveyor 150. This advancing movement of the conveyor 150 moves the first line on the sheet SS engaged by the ledge 151 into position below the platens 116d, 116e and 116f so that upon operation of these 10 platens during this phase of this cycle of operation an impression will be made in the first line of the sheet SS.

Prior to the time the lobe 103 disengages the rider of contact 106' the lobe 110 engages contact 111 to energize the electromagnets 117d, 117e and 117f and just before the lobe 103 disengages the rider of contact 106', the lobe 110 disengages the rider of contact 111 whereupon the solenoids 117d, 117e and 117f are deenergized and an impression is made, in the manner previously described, in the printing means L, M and N in the first line on the sheet SS carried by the conveyor 20

Likewise prior to the time the lobe 91 disengages the rider of contact 94 the lobe 70 engages the rider of contact 73 which effects energization of the electromagnets 117a, 117b and 117c and just before the lobe 91 disengages the rider of contact 94, lobe 70 disengages the rider of contact 73 whereupon the electromagnets 117a, 117b and 117c are deenergized with the result that an impression is made by the platen 116a. The platens 116b and 116c make no impression in this phase of this cycle of operation inasmuch as no type members are positioned therebelow.

Immediately after the lobe 70 disengages the rider of contact 73, lobe 75 engages the rider of contact 78 whereupon solenoid 147 is energized and the conveyor 133 is advanced so that the first sheet S¹ which in this phase of operation has been in the printing means D is advanced into the printing means E and the second sheet S² is advanced into the printing means D, the lobe 75 disengaging the rider of contact 78 shortly after effecting energization of solenoid 147 to enable operation of the conveyor advancing means in the manner previously described.

In this phase of this cycle of operation the printing means L, M and N print all three lines of the address or record entered in the register relays of the group A on the sheet SS while printing means D prints the first line of the address or record entered in the group A of register relays on the sheet S¹.

Immediately after the impressions are made in the printing means, as above described, the lobe 91 disengages the rider of contact 94, the lobe 103 disengages rider of contact 106', and the notch 82 moves into alignment with the rider of contact 85 whereupon shift relays 25, 30, 32 and 106 are deenergized and contact 85 opens freeing conductors 192, 185 and 175 from ground. The freeing of conductors 185 and 192 is without effect in this phase of this cycle of operation inasmuch as no register relays are locked up in the third row of group B nor in the second row of the group C. However, when the conductor 175 is freed from ground the locked-up register relay 14 in the first row of the group A is deenergized as 70 would be any other locked-up register relays in this row of register relays.

Deenergization of shift relay 106 opens contact 223 to free conductor 224 from ground and thereby deenergize electromagnet 157. This permits 75

spring 156 to reposition pawl 155 to enable advancing of conveyor 158 and sheet SS in the next phase of the cycle of operation.

After the time the contact bars 37, 38 and 39 were freed from ground the rollers 54 and 55 and 56 and 57 fed the card X¹ from association with the contact bars and the picker 43 and these rollers positioned the card X² above the contact bars and this operation is completed before the end of 10 this phase of this cycle of operation.

Notch 82 quickly passes from association with the rider of contact 85 whereupon the contact 85 is again closed and this contact remains closed thereafter until the first phase in the next cycle 15 of operation. By the time the rider of contact 85 passes out of the notch 82 all register relays held locked under control of this contact will have been released and the first phase of the first cycle of operation will be complete.

20 Second phase—first cycle

At the start of this cycle of operation the lobe 65 engages the rider of contact 68 and the lobe 98 engages the rider of contact 101 and therefore the transfer relay 35 is energized and ground is applied to the contact bars 37, 38 and 39. Inasmuch as the transfer relay 35 is energized at this time and by reason of the perforations in the card X² above the contact bars 37, 38 and 39 the 25 register relays 179, 180, 181 and 182 in the group B will be energized and locked up in the manner previously described.

Immediately after this operation the lobe 65 disengages the rider of contact 68 and the lobe 98 disengages the rider of contact 101 and the transfer relay 35 is deenergized and the contact bars 37, 38 and 39 are freed from ground. Lobe 92 on cam 89 will then engage the rider of contact 95 whereupon shift relays 28, 33 and 26 will 40 be energized. The energization of shift relay 33 will be without effect inasmuch as no register relays in the group C are locked up at this time. The energization of the shift relay 28 effects energization of the solenoid 127a of the printing 45 element of the printing means D. The energization of the shift relay 26 effects energization of the solenoid 127b of the printing element of the printing means E.

Simultaneously with the closing of the contact 50 95 the lobe 103 engages the rider of the contact 105 which closes and effects energization of the shift relay 107 whereupon the solenoid 127d of the printing element of the printing means L is energized as are the solenoids 126e and 127e of 55 the printing element of the printing means M and the solenoid 126f of the printing element of the printing means N.

Upon the energization of shift relay 107 electromagnet 157 is energized to advance the conveyor 158 and therefore the sheet SS to dispose 60 the second line of this sheet in alignment with the platens 116d, 116e and 116f.

Prior to the time the lobe 92 disengages the rider of contact 95 and the lobe 103 disengages 65 the rider of contact 105 the lobes 70 and 110 will effect closing of the contacts 72 and 112 to energize the electromagnets in all of the printing means, and prior to the opening of the contacts 95 and 105 these electromagnets are deenergized 70 whereby impressions are made. The energization of the electromagnet 111e in this instance is without effect inasmuch as no printing element 115c is disposed therebelow.

In this operation the printing means L, M and 75 N make an impression in the second line on the

sheet SS. Furthermore the printing means E in this phase of this cycle of operation prints the second line on the sheet S¹ which in the previous phase of this cycle of operation received an impression in the first line thereof from the printing means D. The printing means D at this time prints the first line on the second sheet S².

Immediately after these impressions are made the shift relays 28, 33, 26 and 107 are deenergized and likewise the contact 86 opens whereupon the locked-up register relays in the second row in the group A and the first row in the group B are released. The sheets S¹ and S² are also advanced by operation of the solenoid 147 so that at the end of this phase of operation the first 15 sheet S¹ is in the printing means F, the second sheet S² is in the printing means E, and the third sheet S³ is in the printing means D.

Shortly after disengagement of the lobe 98 from the rider of contact 101 the rollers 54 and 20 55 and 56 and 57 ejected the card X² from association with the contact bars 37, 38 and 39 and the picker 43 and these rollers positioned the card X³ over these contact bars.

25 Third phase—first cycle

In initiating the third cycle of operation the lobe 65 engages the rider of contact 67 and the lobe 98 engages the rider of contact 100 whereupon the transfer relay 36 is energized and the 30 contact bars 37, 38 and 39 are grounded. Under control of the perforations in the card X³ the register relays 187, 188, 189 and 190 in the group C are energized and locked up.

As soon as these register relays are locked up 35 the lobe 65 disengages the rider of contact 67 and the lobe 98 disengages the rider of contact 100. Then the lobe 98 engages the rider of contact 96 and the lobe 103 engages the rider of contact 104. Closing of contact 96 effects energization 40 of shift relays 31, 29 and 27 and closing of contact 104 effects energization of shift relay 108.

Under control of the shift relay 27 the solenoids 126c and 127c of the printing element of the printing means F are locked up while under 45 control of the shift relay 29 the solenoids 126b and 127b of the printing element of the printing means E are energized and under control of the shift relay 31 the solenoids 126a and 127a of the printing element of the printing means D are energized. Under control of the shift relay 108 the solenoids 126d and 127d of the printing element 50 of the printing means L are energized as are the solenoid 127e of the printing element of the printing means M and the solenoid 126f of the 55 printing element of the printing means N.

Upon the energization of shift relay 108 electromagnet 157 is energized to advance the conveyor 158 and therefore the sheet SS to dispose 60 the third line of this sheet in alignment with the platens of the printing means L, M and N.

The energization of selected solenoids in the printing means D, E and F and L, M and N selectively position type members below the platens 65 of these printing means and as soon as these type members are disposed below these platens the lobes 70 and 110 engage the contacts 71 and 113 to effect energization of all of the electromagnets of the various printing means and immediately thereafter these electromagnets deenergize 70 whereupon the printing elements make impressions.

In this phase of this cycle of operation the printing means L, M and N print the record entered in the group C on the third line of 75

the sheet S_5 . The printing means F prints the third line on the sheet S^1 , the printing means E the second line on the sheet S^2 and the printing means D the first line on the sheet S^3 .

- 5 Immediately after these impressions are made the lobe 93 disengages the rider of contact 96 and the lobe 103 disengages the rider of contact 104 whereupon the shift relays 31 , 21 , 29 and 108 are deenergized and immediately after this 10 the notch 94 moves into alignment with the rider of contact 81 whereupon the register relays in the third row of the group A , in the second row of the group B and the first row of the group C are released.
- 15 Shortly after the disengagement of the lobe 93 from the rider of the contact 104 in this phase of this cycle of operation, the rollers 54 and 55 and 56 and 57 ejected the card X^3 from association with the contact bars 37 , 38 and 39 and the 20 picker 43 and these rollers positioned the fourth card over these contact bars.

Likewise the lobe 75 engaged the contact 76 and effected energization of the solenoid 147 after the platens $116a$, $116b$ and $116c$ had made 25 impressions on the sheets S^3 , S^2 and S^1 and therefore the conveyor 133 was advanced so that the sheet S^1 bearing its three lines of printing was ejected from the machine, the sheet S^2 was moved into the printing means F , the sheet S^3 was moved 30 into the printing means E and the fourth sheet was moved into the printing means D .

In this third phase of the first cycle of operation a sheet is ejected from the conveyor 133 bearing a three-line address and in every phase 35 in every subsequent cycle of operation a sheet bearing a three-line address will be ejected from the conveyor 133 .

At the end of this third phase of this first 40 cycle of operation all register relays in the group A are released as are the register relays in the first and second rows in the group B and the first row in the group C .

First phase—second cycle of operation

45 This cycle of operation is much like the first phase of the first cycle of operation except that in this phase of this cycle of operation impressions will also be made in both the printing means E and F inasmuch as records are locked up in all of the groups A , B and C .

In this phase of this cycle of operation the 50 shift relays 25 , 30 and 32 will be energized as also will be the shift relay 106 . The printing means L , M and N will make an impression in the fourth line on the sheet S_5 while the printing means F will print the third line on the second sheet S^2 , the printing means E will print the second line on the sheet S^3 and the printing means D will print the first line on the fourth sheet. Likewise in this phase of this cycle of 55 operation the sheet S^2 bearing a three-line impression will be ejected, the sheet S^3 will be fed into the printing means F , the fourth sheet into the printing means E and the fifth sheet into the printing means D .

Furthermore, register relays in the first row of the group A , in the third row of the group B , and in the second row of the group C will be 60 released. Hence at the end of this phase of this cycle of operation all of the register relays in the group B will be released so that the record on the sixth card which will be fed into association with the contact bars 37 , 38 and 39 in this phase of this cycle of operation may be en-

tered in the register relays of the group B in the next or second phase of this cycle of operation.

Variation of order of printing in straight line printer

The described connection between the register relays and the straight line printer is such that the first, second and third parts of a record are printed in that order across the sheet. However, it may be desirable to print the parts in a different order and this may be done by merely varying the wiring connections between the printing elements of the straight line printer and the rows of register relays from that shown and described and in this way the third part 15 of the record may be printed first, the first part second and the second part third or any other desired alteration particularly useful for listing purposes may be utilized, the sundry variations being well understood in the art. 20

Hence, I provide cord plug jacks in the conductors extended between the groups of register relays and the printing elements of the printing means L , M and N . In the illustrated form the conductors as 217 leading from the solenoids as 25 $126d$ are connected to jacks 225 and cord plugs as 226 are fitted therein, these cord plugs being connected to the conductors as 217 leading to the contacts as 214 . It will be apparent that by shifting the cord plugs from jack to jack the interconnection of the register relays and line printing means may be varied as desired. 30

Summary

The succeeding phases of the succeeding cycles 35 of operation correspond to those above described and the machine continues to operate so long as cards are fed to the contact bars 37 , 38 and 39 .

The foregoing description of the apparatus details the printing of the first character of each 40 line or part of a record and it is to be understood that the apparatus for printing the other characters in the line would be identical with that described.

Furthermore, the arrangement, as has been explained heretofore, is one adapted to print a three-part record and more specifically a three-line address, but it is to be understood that a greater or less number of parts or lines could be printed by merely duplicating or eliminating a 50 part of the mechanisms shown and described.

One of the very important features of this invention is that a record consisting of a plurality of parts may be employed to effect set-up of printing means so that all parts of the record 55 may be printed simultaneously and also so that parts of the record may be printed successively, and the salient feature of this invention is this arrangement.

Thus while I have shown and described a selected embodiment of my invention which may be used for addressing it is to be understood that the invention is capable of other uses and may be embodied in other forms and I therefore reserve the right to make any and all changes in 60 form, construction and arrangement of parts that may be necessary or desirable in adapting the invention for different uses and installations within the scope of the following claims:

I claim:

1. In a printing machine under control of a record card or the like having a record thereon comprising a plurality of parts, means for successively printing transcriptions of the parts of the record separately, and other means for print- 75

ing transcriptions of said parts of the record simultaneously.

2. In a printing machine under control of a record card or the like having a record thereon comprising a plurality of parts, means for sensing the record, printing means under control of the sensing means, other printing means under control of the sensing means, and means for operating one of the printing means to print transcriptions of the parts of said record separately and successively and for operating the other printing means to print transcriptions of said parts of the record simultaneously.

3. In a printing machine under control of a record card or the like having a record thereon comprising a plurality of parts, two printing means, means for setting up said printing means under control of the record on the card, and means for operating said printing means simultaneously to cause one of said printing means to print a transcription of a part of the record and the other of said printing means to print the aforesaid and other parts of the record.

4. In a printing machine under control of a record card or the like having a record thereon comprising a plurality of parts, two printing means, means for setting up one of said printing means to print a transcription of a part of the record, means for setting up the other printing means to print a transcription of the aforesaid and other parts of the record, and means for effecting printing operations of said printing means after set-up thereof.

5. In a printing machine under control of a record card or the like having a record thereon comprising a plurality of parts, means for sensing the record, two printing means, means for setting up one of said printing means to print a transcription of a part of the record sensed by the sensing means, other means for setting up the other of the printing means to print a transcription of the aforesaid and other parts of the record sensed by said sensing means, and means for effecting operation of said printing means in timed relation with each other.

6. In a printing machine, selectively energizable circuits, two printing means, means for setting up one of said printing means under control of selected of said circuits upon energization of said selected circuits, means for setting up the other of the printing means under control of the aforesaid and other of said circuits upon energization thereof, and means for operating said printing means.

7. In a printing machine, selectively energizable circuits, two printing means, means for setting up said printing means under control of selected of said circuits upon energization of said circuits, and means for operating said printing means simultaneously to cause one of said printing means to print under control of selected of said energized circuits and the other of said printing means to print under control of the aforesaid selected and other of said energized circuits.

8. In a printing machine, selectively energizable circuits, two printing means, means for setting up one of said printing means under control of selected of said circuits upon energization of said selected circuits, means for setting up the other of the printing means under control of the aforesaid and other of said circuits upon energization thereof, means for operating said printing means simultaneously, and means for setting up and operating the first named

printing means under control of said other circuits subsequent to the simultaneous operation of said printing means.

9. In a printing machine, selectively energizable circuits, two printing means, means for setting up one of said printing means under control of selected of said circuits upon energization of said selected circuits, means for setting up the other of the printing means under control of the aforesaid and other selected of said circuits upon energization thereof, means for operating said printing means, and means for deenergizing said selected circuits immediately subsequent to the operation of said printing means.

10. In a printing machine under control of a record card or the like having a record thereon comprising a plurality of parts, two printing means, means for setting up one of said printing means to print a transcription of a part of the record, means for setting up the other printing means to print a transcription of the aforesaid and other parts of the record, means for simultaneously operating said printing means after the set-up thereof, and means for again setting up said one printing means for printing under control of said other parts of the record after the simultaneous operation of said printing means.

11. In a record card-controlled printing machine, storage means, means for sensing a card and entering at least a part of the record thereon in said storage means, two printing means, means for setting up one of said printing means according to a part of the record entered in said storage means, means for setting up the other of the printing means according to the aforesaid and another part of the record entered in said storage means, and means for operating said printing means.

12. In a record card-controlled printing machine, storage means, means for sensing a card and entering at least a part of the record thereon in said storage means, two printing means, means for setting up one of said printing means according to a part of the record entered in said storage means whereby this printing means may be operated to print according to a part of the record entered in said storage means in accordance with which this printing means is set up, means for setting up the other printing means according to the aforesaid and other parts of the record entered in said storage means whereby this printing means may be operated to print according to part of the record entered in said storage means in accordance with which this printing means is set up, and means for simultaneously operating said printing means after the set-up thereof.

13. In a record card-controlled printing machine, storage means, means for sensing a card and entering at least a part of the record thereon in said storage means, printing means, means for setting up said printing means according to a part of the record entered in said storage means whereby said printing means may be operated to print according to the part of the record entered in said storage means in accordance with which the printing means is set up, a second printing means, means for setting up said second printing means according to another part of the record entered in said storage means whereby the second printing means may be operated to print according to the part of the record entered in said storage means in accordance with which said second printing means is set up, a third

- printing means, means for setting up the third printing means according to the parts of the record in accordance with which the first and second printing means are set up, and means for 5 simultaneously operating the first and third printing means and for subsequently effecting operation of the second printing means.
14. In a record card-controlled printing machine, storage means, means for sensing a card 10 and entering at least a part of the record thereon in said storage means, printing means, means for setting up said printing means according to a part of the record entered in said storage means, a second printing means, means for setting up the second printing means according to another part of the record entered in said storage means after the first named printing means has been set up, a third printing means, means for setting up the third printing means according 15 to the parts of the record according to which the first and second printing means are set up and operable to set up said third printing means concurrently with the set-up of the first printing means, and means for simultaneously operating 20 the first and third printing means and for subsequently operating the second printing means.
15. In a record card-controlled printing machine, card feeding means, storage means, means for sensing a card fed by the card feeding means 25 and for entering at least a part of the record thereon in said storage means, printing means, means for setting up said printing means from at least a part of the record entered in said storage means after said card feeding means has fed the card from which a record was entered 30 in the storage means from cooperation with the sensing means, other printing means, means for setting up said other printing means from the aforesaid and other parts of the record entered 35 in said storage means, and means for operating said other printing means prior to the operation of the first named printing means.
16. In a record card-controlled printing machine, card feeding means, storage means, sensing 40 and entering means, operating means for operating said sensing and entering means to sense a card for a record thereon and enter the sensed record in the storage means, printing means, means for setting up said printing means from 45 at least a part of the record entered in said storage means, means for operating the setting up means subsequent to operation of the first named operating means, other printing means, means for setting up said other printing means from the 50 aforesaid and other parts of the record entered in said storage means, and means for operating the last named setting up means prior to the operation of the first named setting up means and subsequent to the operation of the first named operating means.
17. In a printing machine, means for simultaneously sensing a plurality of parts of a record, a printing means for each part of the record, means for successively setting up the printing 55 means to successively print the sensed parts, other printing means for each part of the record, and means for simultaneously setting up said other printing means to simultaneously print the sensed parts.
18. In a printing machine, means for simultaneously sensing a plurality of parts of a record, a printing means for each part of the record, means for successively setting up the printing means to successively print the sensed parts, other printing 60 means for each part of the record, means for simultaneously setting up said other printing means to simultaneously print the sensed parts.
19. In a printing machine, means for simultaneously sensing a plurality of parts of a record, separate storage means for each part of the record and under control of the sensing means, a printing means for each part of the record, means for successively setting up the printing means from the storage means to successively print the sensed parts, other printing means for each part of the record, and means for simultaneously setting up said other printing means from said storage means to simultaneously print the sensed parts.
20. In a printing machine, means for simultaneously sensing a plurality of parts of a record, separate storage means for each part of the record and under control of the sensing means, a printing means for each part of the record, means for successively setting up the printing means from the storage means to successively print the sensed parts, other printing means for each part of the record, means for simultaneously setting up said other printing means from said storage means to simultaneously print the sensed parts.
21. In a printing machine for successively printing related lines of a record, means for separately storing the lines, means for simultaneously sensing the lines and separately entering the lines in the storing means, a printing means for each line, means for successively setting up the printing means each from a separate storing means, other printing means for each line, and means for simultaneously setting up the other printing means from the separate storing means.
22. In a printing machine for successively printing related lines of a record, means for separately storing the lines, means for simultaneously sensing the lines and separately entering the lines in the storing means, a printing means for each line, means for successively setting up the printing means each from a separate storing means, other printing means for each line, means for simultaneously setting up the other printing means from the separate storing means, and means for operating said other printing means simultaneously with the operation of one of the first named printing means.
23. In a printing machine, means for simultaneously sensing a plurality of parts of a record on a card or the like, a register, means for transferring the sensed parts of the record into the register, printing means for separately printing the sensed parts, and means for simultaneously transferring at least two of the sensed parts from the register to the printing means.
24. In a printing machine, means for simultaneously sensing a plurality of parts of a record on a card or the like, a register, means for transferring the sensed parts of the record into the register, printing means for separately printing the sensed parts in side by side relation, means for simultaneously transferring at least two of the sensed parts from the register to the printing means, and means for operating said printing means after the transfer thereto of the sensed parts from the register.
25. In a printing machine, means for successively printing related lines of a record, means

for separately storing the lines, means for simultaneously sensing the lines and separately entering the lines in the storing means, a printing means for each line, means for successively setting up the printing means each from a separate storing means, other printing means for each line, means for simultaneously setting up the other printing means each from a separate storing means, and means for effecting set-up of said other printing means simultaneously with one of the successive set-ups of the first named printing means.

26. In a printing machine, means for simultaneously sensing a plurality of lines of record on a card or the like, a register, means for transferring the sensed lines of the record into the register, printing means for separately printing the sensed lines, means for transferring the sensed lines to the printing means line by line, other printing means for separately printing the sensed lines, and means for simultaneously transferring the sensed lines to said other printing means.

27. In a printing machine, means for simultaneously sensing a plurality of lines of record on a card or the like, a register, means for transferring the sensed lines of the record into the register, printing means for separately printing the sensed lines, means for transferring the sensed lines to the printing means line by line, other printing means for separately printing the sensed lines, means for simultaneously transferring the sensed lines to said other printing means, and means for effecting operation of the last named transferring means simultaneously with one of the successive operations of the first named transferring means.

28. In a printing machine, means for sensing a plurality of parts of a record on a card or the like, a register, means for entering the sensed parts of the record in the register, a plurality of printing means, and means for operating the printing means under control of the register to effect simultaneous printing of selected of the sensed parts in selected of the respective printing means.

29. In a printing machine, means for sensing a plurality of parts of a record on a card or the like, a register, means for entering the sensed parts of the record in the register, printing means, and means for transferring the sensed parts from the register to the printing means and operable to effect operation of the printing means to print the sensed parts in predetermined arrangement, said transferring means including interchangeable parts for varying the predetermined arrangement of the printing of said sensed parts.

30. In a printing machine, means for sensing a plurality of parts of a record on a card or the like, a register, means entering the sensed parts into the register, printing means for separately printing the sensed parts in a predetermined arrangement, and means for simultaneously transferring at least two of the sensed parts from the register to the printing means to effect operation thereof.

31. In a printing machine, means for sensing a plurality of parts of a record on a card or the like, a register, means entering the sensed parts into the register, printing means for separately printing the sensed parts in a predetermined arrangement, means for simultaneously transferring at least two of the sensed parts from the register to the printing means to effect

operation thereof, and means for varying the predetermined arrangement of the printing of the sensed parts.

32. In a printing machine, means for sensing a plurality of parts of a record on a card or the like, a register, means entering the sensed parts into the register, printing means for separately printing the sensed parts in a predetermined arrangement, means for simultaneously transferring at least two of the sensed parts from the register to the printing means to effect operation thereof, and means for varying the operation of the transferring means to thereby vary the predetermined arrangement of the printing of the sensed parts.

33. In a printing machine, means for simultaneously sensing a plurality of parts of a record on a card or the like, a register, means for transferring the sensed parts of the record into the register, printing means for separately printing the sensed parts, means for transferring the sensed parts from the register to the printing means, means for operating said transferring means to simultaneously transfer the sensed parts to the printing means, and means for releasing said register after the transfer of said sensed parts to said printing means.

34. In a printing machine, means for simultaneously sensing a plurality of parts of a record on a card or the like, a register, means for transferring the sensed parts of the record into the register, printing means for separately printing the sensed parts, means for simultaneously transferring at least two of the sensed parts from the register to the printing means, and means for releasing said register after the transfer of said sensed parts to said printing means.

35. In a printing machine, means for simultaneously sensing a plurality of parts of a record on a card or the like, a register, means for transferring the sensed parts of the record into the register, printing means for separately printing the sensed parts in side by side relation, means for simultaneously transferring at least two of the sensed parts from the register to the printing means, means for operating said printing means after the transfer thereto of the sensed parts from the register, and means for releasing said register after the transfer of said sensed parts to said printing means.

36. In a printing machine, means for simultaneously sensing a plurality of lines of record on a card or the like, a register, means for transferring the sensed lines of the record into the register, printing means for separately printing the sensed lines, means for transferring the sensed lines to the printing means line by line, other printing means for separately printing the sensed lines, means for simultaneously transferring the sensed lines to said other printing means, and means for releasing said register after the transfer of the sensed parts.

37. In a printing machine, means for sensing a plurality of parts of a record on a card or the like, a register, means for entering the sensed parts of the record in the register, a plurality of printing means, means for operating the printing means under control of the register to effect simultaneous printing of selected of the sensed parts in selected of the respective printing means, and means for releasing said register after operation of said printing means under control of the register.

38. In a record card-controlled printing machine, storage means, means for sensing a card

- and entering at least a part of the record thereon in said storage means, two printing means, means for setting up one of said printing means according to a part of the record entered in said storage means, means for setting up the other of the printing means according to the aforesaid and another part of the record entered in said storage means, means for operating said printing means, and means for releasing said storage means after the set-up of said printing means. 5
39. In a record card-controlled printing machine, storage means, means for sensing a card and entering at least a part of the record thereon in said storage means, two printing means, means for setting up one of said printing means according to a part of the record entered in said storage means whereby this printing means may be operated to print according to a part of the record entered in said storage means in accordance with which this printing means is set up, means for setting up the other printing means according to the aforesaid and other parts of the record entered in said storage means whereby this printing means may be operated to print according to part of the record entered in said storage means in accordance with which this printing means is set up, means for simultaneously operating said printing means after the set-up thereof, and means for releasing said storage means after the set-up of said printing means. 10
40. In a printing machine, means for simultaneously sensing a plurality of parts of a record, separate storage means for each part of the record and under control of the sensing means, a printing means for each part of the record, means for successively setting up the printing means from the storage means to successively print the sensed parts, other printing means for each part of the record, means for simultaneously setting up said other printing means from said storage means to simultaneously print the sensed parts, and means for releasing said storage means after the set-up of said printing means. 15
41. In an addressing machine controlled by cards or the like bearing records of addresses consisting of a plurality of lines of printing, storage means, means for sensing a card or the like and simultaneously entering the record of an address in the storage means, printing means for separately printing the lines of an address, means for successively setting up the printing means from the storage means to successively print the lines of the address, other printing means for separately printing the lines of an address, and means for simultaneously setting up said other printing means to simultaneously print the lines of the address. 20
42. In a printing machine, means for sensing a plurality of parts of a record, a printing means for each part, means for setting up the printing means to print said parts in predetermined arrangement under control of the sensing means, and means for varying said predetermined arrangement. 25
43. In a printing machine, means for simultaneously sensing a plurality of parts of a record on a card or the like, a printing means for each part and operable to print said parts in predetermined arrangement, means for setting up the printing means under control of the sensing means, and variable means adjustable to vary the predetermined arrangement of the printing of said parts of the record. 30
44. In a printing machine, printing means, selectively energizable circuits for controlling operation of said printing means to print parts of a record in predetermined arrangement, and means for varying the predetermined arrangement of the printing of said parts. 35
45. In a printing machine, means for sensing a plurality of parts of a record on a card or the like, a register, means for transferring the sensed parts of the record to the register, printing means for printing the parts in predetermined arrangement, means for transferring the sensed parts from the register to the printing means, and means for varying the predetermined arrangement of the printing of said parts. 40
46. In a record card-controlled printing machine, storage means, means for sensing a card and entering at least a part of the record thereon in said storage means, printing means, means for setting up said printing means according to a record entered in said storage means whereby said printing means may be operated to print according to the record entered in said storage means, said printing means printing the parts of the record in predetermined arrangement, and means for varying the predetermined arrangement of the printing of said parts. 45
47. In a printing machine for sensing a plurality of lines of record on a card or the like, a register, means for transferring the sensed lines of the record into the register, printing means for separately printing the sensed lines in predetermined arrangement, means for transferring the sensed lines to the printing means, and means for varying the predetermined arrangement of the printing of said parts. 50
48. In a record card-controlled printing machine, storage means, means for sensing a card and entering at least a part of the record thereon in said storage means, two printing means, means for setting up one of said printing means according to one part of the record entered in said storage means, means for setting up the other of the printing means according to a second part of the record entered in said storage means, means for operating said printing means, and variable means operable to enable said other printing means to be set according to said one part of the record and said one printing means to be set according to said second part of the record. 55
49. In a printing machine, means for simultaneously sensing a plurality of parts of a record, a printing means for each part of the record, means for simultaneously setting up said printing means to simultaneously print the sensed parts in predetermined arrangement, and means for varying the predetermined arrangement of the printing of said parts. 60
50. In a printing machine, means for simultaneously sensing a plurality of parts of a record on a card or the like, a register, means for transferring the sensed parts of the record into the register, printing means for separately printing the sensed parts in predetermined arrangement, means for simultaneously transferring at least two of the sensed parts from the register to the printing means, and means for varying the predetermined arrangement of the printing of said parts. 65

CERTIFICATE OF CORRECTION.

Patent No. 2,077,962.

April 20, 1937.

CLYDE SMITH.

It is hereby certified that error appears in the printed specification of the above numbered patent requiring correction as follows: Page 4, first column, line 65, for "means B" read means D; line 67, for "members 115b on the type bar 114b" read members 115a on the type bar 114a; and second column, line 27, for "link 45" read link 145; and that the said Letters Patent should be read with this correction therein that the same may conform to the record of the case in the Patent Office.

Signed and sealed this 11th day of April, A. D. 1939.

Henry Van Arsdale

(Seal)

Acting Commissioner of Patents.
